OVERSHOE

Leslie H. L'Hollier, Waltham, Mass., assignor to
 The B. F. Goodrich Company, New York, N. Y.,
 a corporation of New York

Application August 29, 1939, Serial No. 292,452

5 Claims. (Cl. 36—7.3)

The invention relates to footwear and especially to rubber footwear of the overshoe or galosh type. The invention is useful especially in overshoes of the type having a vamp portion extending upwardly to provide a shield overlying forward portions of the quarters.

The chief object of the invention is to provide an improved attachment of the quarter to the vamp so that while the overshoe is adapted to be effectively retained on the foot, wide opening of the overshoe is made possible so that putting the overshoe on and taking it off are facilitated. A further object is to provide the attachment of the quarter and upper of such construction and location as to be most effective for a hinging action of the vamp and quarters when it is desired to turn down their top portions, individually or together.

Further objects are to provide for strength of attachment with minimum bulk and weight and to provide attractiveness of appearance.

These and further objects will be apparent from the following description, reference being had to the accompanying drawing in which:

Fig. 1 is a perspective view of a woman's overshoe constructed according to and embodying the invention.

Fig. 2 is a perspective view of the same shoe with the shield portion of the vamp turned down.

Fig. 3 is a perspective view of the same shoe with parts broken away to illustrate features of construction.

Fig. 4 is a section taken along the line 4—4 of Fig. 1.

Fig. 5 is a section taken along the line 5—5 of Fig. 1.

The invention as illustrated in the drawing is applied to an overshoe of the women's galosh type in which a vamp 10 is upwardly extended to provide a shield 11 overlying the forward portions of quarters 12, 13 which are adapted to enclose the ankle portion and extend around the rear.

The overshoe comprises a heel 14, a sole 15 to which the upper of the overshoe is secured, a sole filler 16 and an insole 17. The overshoe may be constructed chiefly of rubber, preferably lined and reinforced by a lining 18 of stretchable fabric for the quarters and a lining 19 of stretchable fabric for the vamp. A suitable fastener 20 may be provided at the forward margins of the quarters to secure them beneath the covering shield 11.

In the region overlying the instep of the overshoe the vamp is slotted at 21 at each side there-

of, the slits extending from the sole upwardly across the instep part way as shown in Fig. 3. The forward margins 22 of the quarters are inserted through the slits and preferably partly overlie the outer surface of the vamp where they are secured, as by adhesion. Pieces 23, 24, preferably fabric reinforced as at 25, are mounted at the outside of the upper overlying the slots 21 and are adhered both to the vamp and to the exposed portions of the quarters by an adhesive 26. This provides a strong attachment of the quarters to the vamp and an attractive appearance without requiring an excessively bulky construction.

The location of the attachment well forward on the instep portion of the overshoe and toward the bottom thereof provides a transverse hinging line low on the vamp and the quarters located so as to make possible a very wide opening for putting on and taking off the overshoe. Also, the shield 11 of the vamp and the quarters 12 and 13 may be folded down, either independently or together when not needed, so that a large part of the upper portion of the foot is exposed for ventilation. This is useful especially in changeable weather when rain is intermittent, and it is useful also in theatres and other places where it is inconvenient to remove the shoe and a folding down for ventilation increases comfort to the wearer.

A strong anchorage of the forward margins of the quarters to the vamp is provided without the necessity of extending such margins entirely down to the bottom of the shoe for anchorage to the sole and a material reduction in the bulk of the shoe thus results. At the same time strength of attachment is provided while the hinging line is located well forward on the instep for most effective opening. The rear margins of the vamp 10 may be extended well to the rear of the instep preferably in the region of the shank portion of the shoe as shown so that the shield 11 may be well curved over the quarters to facilitate the retention of its shape resiliently in its upright position.

Variations may be made without departing from the scope of the invention as it is herein-after claimed.

I claim:

1. An article of footwear comprising a quarter portion having a forward margin and a vamp overlying said portion, said vamp being transversely slotted and the forward margin of the quarter extending through the slit in the vamp and being secured thereto at the slotted portion.

2. An article of footwear comprising a quarter portion having a forward margin, a vamp overlying said portion, said vamp being transversely slitted in the region of the instep and the forward margin of the quarter extending through the slitted vamp and being secured thereto at the slitted portion, and a reinforcing piece overlying the slitted portion and adhered both to the vamp and the exposed forward margin of the quarter.
3. A rubber overshoe comprising a sole and an upper thereon including quarters having separable forward margins, a vamp overlying the forward portions of said quarters, said vamp being transversely slitted and portions of the forward margins of the quarters extending through the slits in the vamp, a reinforcing piece overlying the slitted portions of the vamp and adhered both to the vamp and the exposed forward margins of the quarters, and fabric linings adhered to the quarters and vamp, said linings
- extending into the region of the slits in the vamp.
4. A rubber overshoe as defined in claim 3 in which the said reinforcing piece is fabric lined.
5. A rubber overshoe comprising a sole and an upper thereon including quarters extending about the ankle portion and having separable front margins, means detachably securing together said front margins, a vamp extending rearwardly to the shank region and upwardly to provide a shield adapted to cover the front margins of the quarters, said vamp having slits therein extending upwardly part way across the instep portion from the region of the sole, portions of the forward margins of the quarters extending through said slits and being adhered to the outer surface of the vamp, and a reinforcing piece overlying said slits and adhered to the vamp and to the portions of the quarters extending through said slits.
